NECKTIE HOLDER

Fred N. Ashworth, Somerville, Mass.

Application May 3, 1937, Serial No. 140,298

9 Claims. (Cl. 24—49)

This invention relates to a necktie holder, and has for its primary object to provide a device of novel construction which may be utilized to position the end portions of a four-in-hand necktie in correct relation one to the other and to the front of a shirt.

Another object of the invention is to provide a device which will effectively hold a necktie positioned with respect to a shirt and at the same time will be entirely obscured behind the necktie.

Another object of the invention is to provide a device which will grip the necktie at the rear thereof and adjacent to the opposite edges thereof, and which upon being operated to grip the necktie will also function to stretch the tie laterally.

Still another object of the invention is to provide a holding device for a necktie which will not mar or wrinkle the front surface of the tie or otherwise detract from the appearance thereof.

The invention consists in a necktie holder as set forth in the following specification and particularly as pointed out in the claims thereof.

Referring to the drawing:

Fig. 1 is a front elevation of portions of a shirt and four-in-hand necktie, illustrating in dotted lines a necktie holder embodying my invention positioned behind the front portion of the necktie.

Fig. 2 is an enlarged sectional plan view of the necktie holder as taken on the line 2—2 of Fig. 1.

Fig. 3 is a front elevation of the necktie holder also illustrated upon an enlarged scale.

Fig. 4 is an enlarged detail transverse section taken on the line 4—4 of Fig. 3, looking in the direction of the arrows on said line.

Fig. 5 is a front elevation illustrating a modified embodiment of the invention.

Fig. 6 is an enlarged detail transverse section taken on the line 6—6 of Fig. 5 looking in the direction of the arrows on said line.

Fig. 7 is a front elevation illustrating another modified embodiment of the invention.

Like numerals refer to like parts throughout the several views of the drawing.

In the drawing, referring particularly to Figs. 1 to 4 inclusive, 10 represents a portion of the front of a shirt and 11 represents a portion of a four-in-hand necktie which, as made up and in use, has front and rear portions 12 and 13 respectively embodied therein. The portions 12 and 13 of the necktie normally hang loosely with the front or wide portion 12 obscuring the rear or narrow portion 13, but both of these portions may

become easily disarranged with respect to each other and to the front of the shirt 10, in which condition they present an untidy appearance. The holder of this invention is provided for the purpose of securing the portions 12 and 13 of the necktie in correct relation one to the other and to the front of the shirt 10. The holder comprises a spring clip or clamp member 14 adapted to receive the portion 13 of the necktie 11 together with a front edge portion 15 of the shirt 10, thereby securing said tie and shirt portions 13 and 15 respectively one to the other, and a rotatable fastening device 16 which is secured to the clamp members 14 and engages the front portion 12 of the necktie at the rear thereof in a manner to hold said portion 12 correctly positioned with respect to the portion 13 of said necktie as will be hereinafter more fully described.

The clamp member 14 of the holder is preferably constructed of a single piece of wire and embodies therein parallel portions 17 bent at 18 to provide resilient portions 19 which may or may not extend parallel to each other as may be desired, and which are preferably connected one to another at their outer extremities. In securing the portion 13 of the necktie to the portion 15 of the shirt 10, said portions 13 and 15 are inserted in the space between the portions 17 and 19 of the clamp 14, and the portions 19 of said clamp will exert a yielding pressure upon the tie and shirt and hold the same secured one to another.

The fastening device 16 is rotatably mounted in bearings 20 fast to the portions 17 of the clamp member 14 and embodies therein a rod 21 provided with knurled operating knobs 22 at each end thereof. Secured to the rod 21 at suitable locations thereon, preferably adjacent to the knobs 22, are helical fastener members 23 and 24 formed of wire and wound loosely right and left hand respectively around the rod 21 with the coils thereof spaced apart one from another and from the rod 21. The outermost coils of the fastener members 23 and 24 are secured to the rod 21 in any suitable manner as by fusing or soldering, and the innermost coils of said members 23 and 24 terminate in pointed portions or spurs 25 and 26 respectively which are positioned eccentric to the axis of the rod 21 in a manner to penetrate the fabric of the front portion 12 of the necktie 11 when the rod 21 is rotated in the direction of the arrow Fig. 4. The portion 12 of the necktie is pressed lightly against the spurs during the rotation of the rod 21. The fastener members 23 and 24 are positioned to engage the rear side of the portion 12 of the necktie at points

adjacent to the opposite edges thereof, and in 5 rotating said members, after the spurs 25 and 26 have penetrated the tie and obtained a hold upon said opposite edge portions, a continued rotation of the rod 21 will produce a slight lateral stretching action upon the tie, thereby tending to eliminate wrinkles therefrom. The spurs 25 and 26 in penetrating the necktie will only interlock with a few threads of portions 27 of the tie which are 10 folded behind the front face of said tie, and the stretching action upon the tie is produced by the right and left hand helical coils of the fastener members 23 and 24.

In Figs. 5 and 6 of the drawing I have illustrated a modified embodiment of my invention 15 in which a clamp member 28 is constructed of sheet metal and has a fastening device 29 mounted thereon and rotatable in bearings 30 provided upon the clamp member 28. The fastening device 29 embodies therein a rod 31 provided with knurled operating knobs 32 at opposite ends thereof, and fast to said rod 31 at points adjacent to the operating knobs are fastener members 33 constructed of wire extending partly around 20 the rod a slight distance therefrom and constituting spurs 34 which are formed eccentric to the axis of the rod 31 in a manner to easily penetrate the necktie when the fastening device is rotated. The device illustrated in Figs. 5 and 6 is actuated 25 in exactly the same manner to secure a necktie as the device previously described, but there will be no action tending to stretch the tie laterally, and the fastening device can only be rotated approximately one half a turn.

In Fig. 7 still another modified embodiment of 30 the invention is illustrated in which a clamp member 35 constructed of wire has separate and independently operated fastening devices 36 and 37 mounted thereon. The devices 36 and 37 embody therein rods 38 rotatably mounted in bearings 39 fast to the clamp member 35 and are provided with knurled operating knobs 40. The devices 36 and 37 are also provided with fastener members 41 and 42 respectively formed of wire 35 and wound loosely right and left hand respectively around the rods 38 adjacent to the knobs 40. The fastener members 41 and 42 are constructed in exactly the same manner as the members 23 and 24 previously described and function in exactly the same manner to hold a necktie, and the only difference between the operation 40 of the device of Fig. 7 and the device of Figs. 1 to 4 inclusive is that the fastener devices 36 and 37 are actuated separately whereas the devices 23 and 24 are actuated in unison.

I claim:

1. A necktie holder of the character described 45 having, in combination, means to secure the rear portion of a necktie to the front of a shirt, a spur mounted upon said securing means and means to rotate said spur into interlocking relation with the front portion of the necktie, whereby said portions of said necktie are positioned relatively to each other and to said shirt.

2. A necktie holder of the character described 50 having, in combination, a spring clip adapted to secure the rear portion of a necktie to the front of a shirt, a spur rotatably mounted upon said clip, and means to move said spur into interlocking relation with the front portion of the necktie, whereby said portions of said necktie are positioned relatively to each other and to said shirt.

3. A necktie holder of the character described

having, in combination, resilient clamping means 5 adapted to secure the rear portion of a necktie to the front of a shirt, an arcuate spur mounted upon said clamp, and means to rotate said spur into piercing interlocking relation with the front portion of the necktie, whereby said portions of said necktie are positioned relatively to each other and to said shirt.

4. A necktie holder of the character described 10 having, in combination, means to secure the rear portion of a necktie to the front of a shirt, a helical fastening member mounted upon said securing means, and means to rotate said helical member axially into piercing interlocking relation with the front portion of the necktie, whereby said portions of said necktie are positioned 15 relatively to each other and to said shirt.

5. A necktie holder of the character described 20 having, in combination, means to secure the rear portion of a necktie to the front of a shirt, a fastening device rotatably mounted upon said securing means having spurs embodied therein positioned behind rearwardly folded portions of the front portion of the necktie, and means to rotate said fastening device to cause said spurs to 25 interlock with said folded portions whereby the front and rear portions of the necktie are positioned relatively to each other and to said shirt.

6. A necktie holder of the character described 30 having, in combination, resilient clamping means 35 adapted to secure the rear portion of a necktie to the front of a shirt, and a pair of fastening members rotatably mounted upon said clamping means and comprising oppositely wound pointed wires adapted to be rotated into piercing interlocking relation with the front portion of the necktie, whereby said portions of said necktie are positioned relatively to each other and to said shirt.

7. A necktie holder of the character described 40 having, in combination, means to secure the rear portion of a necktie to the front of a shirt, oppositely wound helical fastening members mounted upon said securing means, and means 45 to rotate said helical members axially into piercing interlocking engagement with the front portion of the necktie adjacent to the opposite side edges thereof, whereby said portions of said necktie are positioned relatively to each other and to said shirt.

8. A necktie holder of the character described 50 having, in combination, means to secure the rear portion of a necktie to the front of a shirt, a rod rotatably mounted upon said securing means, operating knobs at opposite extremities of said rod, 55 and oppositely wound pointed helical wires surrounding said rod and fast thereto adjacent to said knobs, said wires being adapted, upon rotation of said rod, to pierce the front portion of the necktie, whereby said portions of said necktie are positioned relatively to each other and to said shirt.

9. A necktie holder of the character described 60 having, in combination, means to secure a portion 65 of a necktie to the front of a shirt, a pointed wire coil mounted upon said securing means, and means to rotate said coil to cause the point thereof to penetrate another portion of said necktie, whereby said portions of said necktie are positioned relatively to each other and to said shirt.

FRED N. ASHWORTH.
